AUTOMATIC SAFETY SHUTOFF SYSTEM FOR
GAS BURNERS COMPRISING TWO LATCH-
ING MEANS

Floyd M. Wolfe, Denver, Colo.

Application March 4, 1947, Serial No. 732,185

11 Claims. (Cl. 158—117.1)

1

This invention relates to a gas burner safety control and has for its principal object the provision of means for controlling the gas supply to a gas burner in consequence of the operation of the pilot light employed for igniting the burner so that gas cannot flow to either the burner or the pilot burner unless the latter is properly ignited.

Accidents often occur from the use of gas burners due to the fact that the pilot burner will become extinguished from down drafts or from other causes. The thermostat controlling the main valve will then turn the gas into the main burner, filling the fire-box with raw explosive gas.

An object of this invention is to provide a device which will automatically close the gas supply line to the main burner whenever the pilot burner becomes extinguished, and to provide means which will prevent the main gas supply line from being opened until the pilot burner has been properly ignited.

Devices have been arranged to electrically shut off the gas supply to a main burner in case the pilot burner is extinguished. These devices, however, do not operate to shut off the supply of gas to the pilot burner, and as a result the raw pilot burner gas will often fill the fire-box to an explosive extent.

Another object of this invention is to provide means which, when the pilot burner is accidentally extinguished will not only shut off the main burner gas supply but will also shut off the pilot burner gas supply; and to provide safe means for turning gas to the pilot burner for re-ignition purposes.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved burner control in the normal operating position;

Fig. 2 is a longitudinal section thereof taken on the line 2—2, Fig. 1;

Fig. 3 is a vertical cross section taken on the line 3—3, Fig. 2;

Fig. 4 is a horizontal cross section taken on the line 4—4, Fig. 5;

2

Fig. 5 is a vertical section taken on the line 5—5, Fig. 2, with the control shown in the starting or igniting position;

Fig. 6 is an enlarged, vertical, detail section taken on the line 6—6, Fig. 4;

Fig. 7 is a similarly enlarged, vertical detail section taken on the line 7—7, Fig. 4; and

Fig. 8 is a similarly enlarged, horizontal detail section through the pilot burner, taken on the line 8—8, Fig. 3.

The invention is designed to control the gas supply line to any conventional gas burner by means of a control valve, designated in its entirety by the numeral 10. The control valve contains an intake chamber 11 and an outlet chamber 12 provided with the usual threaded pipe receiving sockets 13. The flow of gas from the chamber 11 to the chamber 12 is controlled by means of a disc valve 14 positioned to contact a valve seat 15.

The disc valve 14 is provided with a valve stem 16 which extends upwardly through a suitable packing gland 17 and through a control box 18. The valve stem 16 is provided, within the box 18, with an upper flange 19 and a lower flange 20. A compression spring 21 acts against the upper flange 19 to urge the valve disc 14 towards its seat 15.

The valve 14 is supported in the open position of Fig. 2 by means of a swinging latch 23 carried by a locking lever 22 mounted on latch pin 25. The latch 23 is constantly urged toward the upper flange 19 by a suitable torsion spring 24. The spring 24 engages the lever 22 at its one extremity and engages a fulcrum pin 69 at its other extremity so that the reaction of the spring is carried to the lever 22. The lower extremity of the locking lever 22 is provided with a pointed tooth 26 which engages a toothed rack 27 on the upper surface of a horizontally positioned control bar 28.

The control bar 28 is slidably mounted so that it may be moved back and forth through the medium of a connecting rod 29 which extends to a thermostatically expandible bellows 30. The bellows 30 is positioned in a protecting frame 31 positioned adjacent the fire box or burner of the heat plant. A supporting tube 32 extends from the frame 31 to the control box 18 about the connecting rod 29.

The bellows 30 terminates in an expansion chamber 33 positioned adjacent the pilot flame from a pilot burner tip 34 so that the head thereof will expand the bellows 30 so as to force the control bar 28 to the left in Fig. 2. This move-

ment causes the rack 27 to act against the tooth 26 to swing the lever 22 toward the upper flange 19 to hold the latch 22 thereunder and maintain the valve 14 in the open position.

Should the pilot burner become extinguished the bellows 30 will contract, moving the control rod to the right in Fig. 2 so as to swing the lever 22 to the broken line position of Fig. 2. This allows the valve 14 to drop under the influence of the spring 21 so as to shut off the supply of gas to the outlet chamber 12 and to the main burner.

The control rod 28 is provided on its under side with a second toothed rack 35 which acts against a pointed extremity 36 on a second locking lever 37 to swing the latter to and from the lower disc 20. The second lever 37 is provided with a latch member 38 which, when the control rod 28 moves to the right, swings above the lower flange 20, as shown in broken line in Fig. 2, to prevent the valve 14 from being opened. When the control rod 28 moves to the left under the influence of the expanding bellows 30 the second locking lever 37 will be swung to the solid line position of Fig. 2 so as to release the flange 20 and allow the valve 14 to be opened, as will be later described.

The gas is fed to the pilot burner through a gas tube 39 extending to a pilot burner valve housing 40 formed, or secured, on the side of the control valve 10. Two passages 41 and 42 communicate between the pilot burner housing 40 and the intake chamber 11 and the outlet chamber 12, respectively. The passages 41 and 42 are controlled by means of a two-way plug valve 43 maintained in a tapered valve seat by means of a valve spring 44.

The plug valve 43 is provided with two ports 45 and 46 which open the passages 41 and 42, respectively, to the hollow interior of the valve 43. The ports 45 and 46 are positioned at right angles to each other. The gas from either passage discharges from the hollow interior of the valve 43 through a discharge port 47 to an annular receiving chamber 48 communicating with the gas tube 39.

The pilot burner valve 43 may be rotated from a valve shaft 49 which extends through a cam box 50 and terminates in a control handle 51. The control handle 51 is constantly urged toward the position of Figs. 1 and 3 by means of a return spring 52. To open the port 46 to the passage 41 it is necessary to manually rotate the handle 51 against the action of the spring 52 to the position of Fig. 5.

The valve shaft 49 is provided with a cam 53 against the cam surface of which a cam follower 54 bears. The cam follower is pivoted on a cam pin 55 and is provided with a bifurcated spring arm 56 which extends beneath the lower flange 20. When the lever 51 is swung from the position of Fig. 1 to the position of Fig. 5, the cam 53 will force the follower 54 downwardly, putting tension in the spring arm 56 to urge the valve stem 16 to open the valve 14. The lever 51 is temporarily held in the position of Fig. 5 by means of a swinging dog 57, which engages a lug 58 carried on a rotatable lug shaft 59 which extends to a position alongside the valve stem 16.

The shaft 59 is connected to the lower flange 20 by means of an actuating lever 60 so that when the stem 16 moves upwardly to the open position, the lug 58 will be rotated out of the path of the latch 57 to allow the spring 52 to snap the handle 51 back to the normal operating position of Fig. 1.

The lug shaft 59 also carries a second lug 61 positioned at right angles to the first lug 58. When the valve 14 opens, the lug shaft will be rotated to bring this second lug in the path of a second dog 67, mounted on the cam 53, to lock the valve 43 in the normal position of Fig. 1.

Let us assume that the mechanism is in the position of Fig. 2 and that gas is flowing from the intake chamber 11 to the outlet chamber 12 and from thence to the burner and through the passage 42, valve 43, and tube 39 to the pilot light. The mechanism remains in this position as long as the pilot light is lighted.

Now let us assume that the pilot burner becomes extinguished. This causes the bellows 30 to contract to pull the latch member 22 from beneath the upper flange 19 to the spring 21 to force the valve 14 against the seat 15 and shut off all gas, including the gas to the pilot burner tip 34. It is now impossible to turn any gas to the burner, for the valve 14 is locked closed by means of the locking lever 37. The lever 51 remains in the operating position of Fig. 1.

To start the burner, the lever 51 is turned from the position of Fig. 1 to the starting or igniting position of Fig. 5. This allows gas to flow from the intake chamber 11 through the passage 41, and the tube 39 to the pilot burner. The handle is automatically locked in this position by the dog 57 and lug 58. The pilot flame is now ignited.

As soon as the pilot flame has heated the expansion chamber 30 sufficiently, the bellows will expand to the left swinging the locking lever 37 away from the flange 20 and allowing the spring arm 56 to snap the valve 14 open and allowing the flange 19 to move past the latch member 22 to lock the valve open. In moving to the open position the flange 20 will, through the medium of the arm 60, rotate the shaft 59 to swing the lug 58 from the path of the dog 57. This allows the spring 52 to return the pilot burner valve 43 to the position of Fig. 3 so that gas will flow through the passage 42 and port 46 from the outlet chamber 12 to the pilot burner. When the handle 51 reaches the position of Figs. 1 and 3 the second dog 57 will engage the second lug 61 to lock the valve 43 open and to prevent the pilot burner gas from being shut off.

Thus it can be seen that gas cannot flow to the burner unless the pilot burner has been lighted, and that no gas can flow to the pilot burner until it is reignited.

There might be emergencies arise in which the pilot burner would become extinguished before it had heated the expansion bellows to a point to operate the valve, and since the pilot burner valve is locked in the open position of Fig. 3 by the latch member 61, it would be impossible for the operator to shut off the gas to the extinguished pilot burner.

For such cases, a sliding sleeve 62 may be provided on the shaft 59 for carrying the lugs 58 and 61. This sleeve is keyed to the shaft 59 by means of a key 63 riding in an elongated slot 64 in the sleeve 62. Outward movement of the sleeve 62 is prevented by means of a tubular cap 65 which extends to the exterior of the cam box 50. The cap is normally prevented from moving outward by means of a boss 66 which bears against the side of the box 50. When the cap 65 is turned to one position the boss 66 may exit through a slot 67 to allow the cap to move outward so that the lug 58 may move out of the way of the dog 57 so that the spring 52 may

return the pilot burner valve to the inoperative position.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. In combination, a pilot burner; a thermo-expansible unit placed to receive heat from said pilot burner; a control bar longitudinally movable by said thermo-expansible unit; a main gas valve; a pilot gas valve; a locking latch for holding said main valve open; a second locking latch for holding said main valve closed; and means on said control bar for actuating the second latch to the holding position and releasing the first latch when said thermo-expansible unit contracts and for actuating the first latch to the holding position and releasing the second locking latch when said thermo-expansible unit expands.

2. A control for gas burners comprising: a pilot burner; a thermo-expansible unit placed to receive heat from said pilot burner; a control bar longitudinally movable by said thermo-expansible unit; a main gas valve; spring means urging said main valve closed; a pilot burner valve; a locking latch for holding said main valve open; engaging means operable from said control bar for actuating said latch to the holding position; releasing means operable by said control bar for releasing said latch from said main valve so that said spring means will close the latter when the pilot burner is extinguished; and means operable from said pilot burner valve for exerting an opening action on said main gas valve when said pilot burner is operated to turn gas to said pilot burner.

3. In a device of the class described, a main valve body having an intake chamber and a discharge chamber; a valve disc controlling the flow from said intake chamber to said discharge chamber; resilient means urging said valve disc to the closed position; a valve stem extending from said disc; a control bar extending laterally across said valve stem; a pilot burner; a thermo-expansible member positioned adjacent said pilot burner; a connecting rod connected between said thermo-expansible member and said control bar for moving the latter transversally of said valve stem in consequence of the movements of the former; a projection on said valve stem; a swinging latch adapted to engage said projection to hold said valve disc open; and means on said control bar positioned to engage said latch to release the latter when said pilot burner is extinguished to allow said resilient means to close said valve.

4. In a device of the class described, a main valve body having an intake chamber and a discharge chamber; a valve disc controlling the flow from said intake chamber to said discharge chamber; resilient means urging said valve disc to the closed position; a valve stem extending from said valve disc; a control bar extending transversally across said valve stem intermediate the extremities thereof; a pilot burner; a thermo-expansible member positioned adjacent said pilot burner; a connecting rod connected between said thermo-expansible member and said control bar for moving the latter transversally of said valve stem in consequence of the movements of the former; a projection on said valve stem at

one side of said control bar; a swinging latch adapted to engage said projection to hold said valve disc open; means on said control bar for engaging said latch to release the latter from said projection when said pilot burner is extinguished; a second projection on said valve stem on the other side of said control bar; a second swinging latch for engaging said second projection to hold said valve disc closed; and means operable from said control bar for releasing second said latch from said second projection when said pilot burner is ignited.

5. In a device of the class described, a main valve body having an intake chamber and a discharge chamber; a valve disc controlling the flow between said chambers; a pilot burner; means for opening and closing said valve disc in response to the heat from said pilot burner; a pilot valve housing positioned adjacent said main valve body; a hollow ported pilot burner valve in said latter housing controlling the flow to said pilot burner; a first passage in said body and housing extending from said intake chamber to said pilot burner valve; a second passage in said body and housing extending from said discharge chamber to said pilot burner valve; a third passage in said pilot valve housing; means for rotating said pilot burner valve when said main valve is closed so as to place the first passage in communication with the third passage so as to connect the pilot burner with the intake chamber; and spring means for returning said pilot burner valve to its former position to place the second passage in communication with the third passage so as to connect the pilot burner with said discharge chamber when the valve disc is open.

6. A control for gas burners comprising: a pilot burner; a thermo-expansible unit placed to receive heat from said pilot burner; a control bar longitudinally movable by said thermo-expansible unit; a main burner valve having an intake and a discharge side; spring means urging said main valve closed; a locking latch for holding said main valve open; engaging means operable by said control bar for actuating said latch to the holding position when said pilot burner is ignited; releasing means operable by said control bar for releasing said latch to allow said main valve to close when the pilot burner is extinguished; a pilot burner valve, there being a first gas passage communicating between the intake side of said main valve and said pilot burner valve and a second gas passage communicating between the discharge side of said main valve and said pilot burner valve and a third gas passage communicating between said pilot burner and said pilot burner valve; and a port in said pilot burner valve positioned to register with each of said passages, said ports being interconnected in said pilot burner valve so that rotation of the pilot burner valve will place either the first or second passage in communication with said third passage and said pilot burner.

7. A control for gas burners comprising: a pilot burner; a thermo-expansible unit placed to receive heat from said pilot burner; a control bar longitudinally movable by said thermo-expansible unit; a main burner valve having an intake and a discharge side; spring means urging said main valve closed; a locking latch for holding said main valve open; engaging means operable by said control bar for actuating said latch to the holding position when said pilot burner is ignited; releasing means operable by said control

bar for releasing said latch to allow said main valve to close when the pilot burner is extinguished; a pilot burner valve, there being a first gas passage communicating between the intake side of said main valve and said pilot burner valve and a second gas passage communicating between the discharge side of said main valve and said pilot burner valve and a third gas passage communicating between said pilot burner and said pilot burner valve; a port in said pilot burner valve positioned to register with each of said passages, said ports being interconnected in said pilot burner valve so that rotation of the pilot burner valve will place either the first or second passage in communication with said third passage and said pilot burner; a manual handle for rotating said pilot valve to place said first passage in communication with said pilot burner; and automatic means operable by said main gas valve and acting to return said pilot valve into communication with said second passage when said main valve is opened.

8. A control for gas burners comprising: a pilot burner; a thermo-expansible unit placed to receive heat from said pilot burner; a control bar longitudinally movable by said thermo-expansible unit; a main burner valve having an intake and a discharge side; spring means urging said main valve closed; a locking latch for holding said main valve open; engaging means operable by said control bar for actuating said latch to the holding position when said pilot burner is ignited; releasing means operable by said control bar for releasing said latch to allow said main valve to close when the pilot burner is extinguished; a pilot burner valve, there being a first gas passage communicating between the intake side of said main valve and said pilot burner valve and a second gas passage communicating between the discharge side of said main valve and said pilot burner valve and a third gas passage communicating between said pilot burner and said pilot burner valve; a port in said pilot burner valve positioned to register with each of said passages, said ports being interconnected in said pilot burner valve so that rotation of the pilot burner valve will place either the first or second passage in communication with said third passage and said pilot burner; a manual handle for rotating said pilot valve to place said first passage in communication with said pilot burner; means for locking said pilot valve in communication with said first passage; a spring urging said pilot valve into communication with said second passage; and releasing means operable from the opening action of said main valve for releasing said locking means so that said latter spring may return said pilot valve into communication with said second passage when said main valve is opened.

9. A control for gas burners comprising: a pilot burner; a thermo-expansible unit placed to receive heat from said pilot burner; a control bar longitudinally movable by said thermo-expansible unit; a main burner valve having an intake and a discharge side; spring means urging said main valve closed; a locking latch for holding said main valve open; engaging means operable by said control bar for actuating said latch to the holding position when said pilot burner is ignited; releasing means operable by said control bar for releasing said latch to allow said main valve to close when the pilot burner is extinguished; a pilot burner valve, there being a first gas passage communicating between the in-

take side of said main valve and said pilot burner valve and a second gas passage communicating between the discharge side of said main valve and said pilot burner valve and a third gas passage communicating between said pilot burner and said pilot burner valve; a port in said pilot burner valve positioned to register with each of said passages, said ports being interconnected in said pilot burner valve so that rotation of the pilot burner valve will place either the first or second passage in communication with said third passage and said pilot burner; a manual handle for rotating said pilot valve to place said first passage in communication with said pilot burner; automatic means operable by said main gas valve and acting to return said pilot valve into communication with said second passage when said main valve is opened; locking means automatically engaging said pilot valve to lock the latter in communication with said second passage when said main valve is opened; and a releasing member extending from said main valve to said pilot valve and arranged to release said locking means when said main valve closes.

10. A control for gas burners comprising: a pilot burner; a thermo-expansible unit placed to receive heat from said pilot burner; a control bar longitudinally movable by said thermo-expansible unit; a main burner valve having an intake and a discharge side; spring means urging said main valve closed; a locking latch for holding said main valve open; engaging means operable by said control bar for actuating said latch to the holding position when said pilot burner is ignited; releasing means operable by said control bar for releasing said latch to allow said main valve to close when the pilot burner is extinguished; a pilot burner valve, there being a first gas passage communicating between the intake side of said main valve and said pilot burner valve and a second gas passage communicating between the discharge side of said main valve and said pilot burner valve and a third gas passage communicating between said pilot burner and said pilot burner valve; a port in said pilot burner valve positioned to register with each of said passages, said ports being interconnected in said pilot burner valve so that rotation of the pilot burner valve will place either the first or second passage in communication with said third passage and said pilot burner; a manual handle for rotating said pilot valve to place said first passage in communication with said pilot burner; automatic means operable by said main gas valve and acting to return said pilot valve into communication with said second passage when said main valve is opened; a cam mounted on said pilot valve; a spring arm pivoted intermediate its extremities and contacting said cam at its one extremity and said main valve at its other extremity, said cam being contoured to cause said spring arm to exert an opening action on said main valve when said pilot valve is rotated manually by said manual handle.

11. A control for gas burners comprising: a pilot burner; a thermo-expansible unit placed to receive heat from said pilot burner; a control bar longitudinally movable by said thermo-expansible unit; a main burner valve having an intake and a discharge side; spring means urging said main valve closed; a locking latch for holding said main valve open; engaging means operable by said control bar for actuating said latch to the holding position when said pilot burner is ignited; releasing means operable by said control

bar for releasing said latch to allow said main valve to close when the pilot burner is extinguished; a pilot burner valve, there being a first gas passage communicating between the intake side of said main valve and said pilot burner valve and a second gas passage communicating between the discharge side of said main valve and said pilot burner valve and a third gas passage communicating between said pilot burner and said pilot burner valve; a port in said pilot burner valve positioned to register with each of said passages, said ports being interconnected in said pilot burner valve so that rotation of the pilot burner valve will place either the first or second passage in communication with said third passage and said pilot burner; a manual handle for rotating said pilot valve to place said first passage in communication with said pilot burner; automatic means operable by said main gas valve and acting to return said pilot valve into communication with said second passage when said

main valve is opened; and a manually actuated release device for releasing said latter locking means when desired.
